UNITED STATES PATENT OFFICE

2,559,547

MACHINE FOR MAKING AN ELECTRODE ASSEMBLY

Price L. Reed, Royersford, Pa., assignor to Superior Tube Company, Philadelphia, Pa., a corporation of Pennsylvania

Application October 12, 1949, Serial No. 120,911

9 Claims. (Cl. 219—4)

1

This invention relates to the manufacture of cathodes for thermionic tubes and has particular reference to the disc-type of cathode which is used in various cathode ray tubes, television pick-up tubes and tubes of the so-called lighthouse construction.

In tubes of the type just mentioned the thermionic emission is obtained from a relatively small, cup-shaped disc coated with alkaline earth oxides. The disc must be rigidly mounted within the tube a few thousandths of an inch from a grid member and in accurate parallel alignment therewith. The disc is supported by a metal tubular member which may be of any conventional form, i.e., seamless or of lock seam, welded, welded and drawn, boxed, or wrap-around ribbon type, and also serves as a means of conducting heat to the disc or cup carrying the oxides to heat it to electron-emitting temperature. An insulated tungsten, molybdenum or similar wire is usually placed within the tube to provide sufficient heat by electrical resistance to make possible attainment of the proper temperature.

In order to support the cathode assembly, ceramic or similar heat-resistant insulators are employed. These insulators, generally in the form of a flat disc, are mounted on the tubular member prior to the attachment of the cup to the tubular member. The attachment of the cup to the tubular member is generally accomplished by inserting the tubular member into the cup which fits as a snug cap over the end of the tube and then welding the cup to the tube.

It is an object of this invention to maintain an accurate dimension longitudinally between the face of the disc and the face of the cup while welding the cup to the tube supporting the disc.

Another object of this invention is to maintain accurate parallel plane alignment between the face of the disc and the end face of the cup while welding the cup to the tube supporting the disc.

In my Patent No. 2,476,454, issued July 19, 1949, there is disclosed a machine for making the cathode assembly which welds the cap to the tube one weld at a time and rotates the assembly to successive welding positions under a single welding electrode.

It is a further object of this invention to provide means for automatically making a plurality of welds evenly spaced around the periphery of the cap without moving the assembly until the welding is completed.

These and other objects of the invention will become apparent from the following description, read in conjunction with the accompanying drawings, in which:

2

Figure 1 is a plan view of the apparatus involved;

5 Figure 2 is an axial section of the welding and gauging means taken on the plane indicated by 2—2 in Figure 1 above the mounting plate, and an elevation of the apparatus below the mounting plate;

10 Figure 3 is a side elevation of the apparatus showing the control mechanism lying below the mounting plate;

Figure 4 is a front elevation of the gauging and welding means and the mechanism lying below the mounting plate;

15 Figure 5 is a front elevation of the welding means, as viewed from between the gauging means and the welding means;

20 Figure 6 is an enlarged fragmentary side elevation, entirely in section, showing the cathode assembly held by the gauging means in position to be welded with two of the welding electrodes in position for welding;

Figure 7 is a diagram of the electrical circuit involved; and

25 Figure 8 is a side elevation of the welding and gauging means shown in the lower portion of Figure 1.

Referring to the figures there is shown a driving motor 2 coupled through the shaft 3 to a speed reducer 4 which, in turn, drives the shaft 30 5 and the one-revolution clutch 6. The one-revolution clutch 6 may be of any conventional type employing a solenoid controlled release electrically energized through the lead wires 8 and 10. When the one-revolution clutch is energized, 35 sprocket wheel 12 which is affixed to the shaft 11 driven by the clutch 6 will rotate for one revolution driving the chain 14. The chain 14 drives the sprocket wheel 16. The sprocket wheel 16, having twice the number of teeth of the sprocket 40 wheel 12, will be driven one-half a revolution with each revolution of the sprocket wheel 12 or with each operation of the one-revolution clutch 6. Inasmuch as the motor 2, the speed reducer 4 and the one-revolution clutch 6 may take the 45 form of any conventional apparatus of this type, and are not essential parts of the present invention, they will not be described in detail.

The welding apparatus shown generally at 1 in Figure 2 is supported by the supporting member 18 which is mounted on the mounting plate 20. Passing through a bore in the supporting member 18 is the insulating sleeve 22 which is held in position within the member 18 by the set screws 24.

55 Mounted on the portion of the insulating sleeve 22 extending outwardly from the left side of supporting member 18, as viewed in Figure 2, is the

member 26 which is held in position on the insulating sleeve by means of set screws 28. Rotatably mounted on the member 26 is the member 30 which is retained in proper position by virtue of its bearing on the face 32 of the member 26 and its bearing on the insulating collar 34 which is located between the extended flange portion 36 of the member 30 and the support 18. Rigidly mounted to the extended flange portion 36 of the member 30 is the sprocket wheel 16 which is driven as the result of operation of the one-revolution clutch 6, and causes the member 30 to rotate for one-half a revolution about the stationary member 26 with each operation of the one-revolution clutch.

Mounted within the extended rim portion 31 of the rotatable member 30 are a pair of cam members 33 which are adapted to rotate with the member 30 and depress the electrode mounting assemblies as will be hereinafter described. Mounted on the external surface of the rotatable rim 31 are four buttons or projections 35.

Slidably mounted within the radially disposed slots 37, within the stationary member 26, are the electrode mounting blocks 38. Each of the blocks 38 is slidably retained within the slots 37 by the two retaining plates 39 which are affixed to the stationary member 26 by screws 41. The electrode mounting blocks are urged in radially outward positions by the spring 23 acting between the extended portion 25 of the block 38 and the inner end of the radially extending slots 21 in the stationary member 26.

The machine, as described herein, contains four electrodes and four electrode mounting assemblies. It will be obvious, however, that any number of pairs of electrodes and electrode mounting assemblies may be used within the limitations imposed by the space limitations and the proportionate sizes of the parts involved. The following description of the electrode, and electrode mounting assemblies, is directed to one assembly only, it being understood that all of the assemblies are alike.

Mounted on the electrode supporting block 38 by means of the screws 40 is the electrode mounting yoke 42. The mounting yoke 42 is insulated from the support block 38 by means of a sheet of insulating material 44 lying between the yoke 42 and the block 38 and the insulating sleeves 46 surrounding each of the mounting screws 40. Contained within bores passing through the extended ends of the mounting yoke 42 is the electrode sleeve 48 to which is affixed a collar 50. Mounted over the electrode sleeve 48 is a spring 52. The inner end of the spring bears against a collar 50 and the outer end bears against the inside of the outer extended portion of the yoke 42. Mounted within the electrode sleeve 48 is the electrode holder 54, in the inner end of which is inserted the electrode tip 56.

Clamped to the inner ends of the electrode holders are the conductor lead mounting blocks 60, 61, 62 and 63. Connected to the blocks 60 and 61 are the flexible lead wires 64 and 65, joining the blocks 60 and 61 to the welding cable 66, and connected to the blocks 62 and 63 are the flexible lead wires 67 and 68 joining the blocks 62 and 63 to the welding cable 69. The welding cables 66 and 69 are connected to a conventional type welding current timer 70 which receives power from power lines 153 and 155.

Each of the conductor lead mounting blocks 60, 61, 62 and 63 serves the additional purpose, when clamped against its associated electrode sleeve by the action of its associated clamping

screw 59, of compressing the sleeve against its associated electrode holder 54, thus firmly retaining the electrode holder 54 in its preestablished position within the sleeve 48. The outer end of the electrode holder is threaded and a nut 58 is provided to facilitate the setting of the position of the electrode holder within the electrode sleeve. For example, the electrode holder 54 is placed within the electrode sleeve 48 in a position inwardly further than will be required. Then the clamping screw 59 is partially tightened and the mounting block will hold the electrode holder in position within the sleeve, and then, by tightening the nut 58, the electrode holder may be drawn outwardly through the sleeve to exactly the desired position, after which the clamping screw 59 is tightened completely.

Mounted within the insulating sleeve 22 in the support member 18 is the sleeve member 71 which is held in position in the sleeve 22 by set screws 72. The member 71 contains a central bore 73 which is threaded at its right hand end as viewed in Figure 2. The partially threaded sleeve member 74 is inserted into the bore 73 and may be adjustably positioned within the member 71 by means of the screw threads and locked into position by the lock nut 75. The sleeve member 74 contains a partially threaded central bore within which is mounted the partially threaded rod 76 which may be adjustably positioned by means of the screw threads and locked in that position within the member 74 by the lock nut 78. The rod 76 has a portion of reduced diameter 79 extending for approximately half its length from the left hand end, as viewed in Figure 2.

Mounted within the enlarged central bore 77 at the left hand of the sleeve member 71, as viewed in Figure 6, is the solid cylindrical member 80. The member 80 is held in position on rod 76 by means of the set screw 82. The member 80 is positioned to bear against the spacer member 84 which, in turn, bears against the end of the sleeve member 74. Mounted in each of three bores 86 uniformly spaced within the member 80 is a plunger member 88 which is urged outwardly by the spring member 90 acting between the plunger rod collar 92 and the plug member 94 in the member 80.

It will be observed that the position of the member 80 may be longitudinally adjusted by turning the sleeve member 74 within the member 71, and that the relation between the left hand end of the rod member 76 and the left hand end of the member 80 may also be adjusted by positioning the rod member 76 within the sleeve member 74.

Also mounted on the base plate 20 is the member 96, containing the gib slot 97, within which is slidably mounted the gib member 98, supporting the member 99 on which is mounted the gauge plate 100 and the micrometer assembly, generally indicated at 101.

The gauge plate 100, which is fixedly mounted to the member 99, has on its upper portion four projections 102 separated by the central bore 103. The end faces 104 of these projections are accurately machined faces lying on a common plane perpendicular to the surface of the bed plate 20 and normal to the longitudinal axes of the rod 76. The micrometer assembly includes the fixed member 105, mounted on the member 99, and containing the threaded central bore 106 within which is mounted the adjustable micrometer stem 107. Attached to the micrometer stem 107 is the conventional micrometer rotatable outer member 108 carrying the usual micrometer scale

markings. Thus, by adjusting the micrometer, the longitudinal distance between the end 111 of the micrometer shaft and the end faces 104 of the gauge plate extension can be accurately adjusted.

Also attached to the base plate 20 is the bracket 142, mounting the limit switch 144 and the limit switch actuating lever 146. Mounted on the lever 146 is the projection 148 which is positioned so as to be depressed by the projections 35 on the rotatable member 30 when the member 30 is rotated. Upon depression, the lever 146 actuates the limit switch 144 closing the circuit therethrough and initiating the operation of the welding timer 70 and causing welding current to flow, as will be hereinafter described.

Mounted below the base plate 20 is the mechanism for actuating the micrometer and the gauge plate mounting gib 98. This mechanism includes the member 112 which is adapted to be extended downwardly and provided with a foot pedal, or other suitable means not shown, which may be actuated by an operator. The member 112 has the flattened upper end portion 113 which is pivotally mounted by means of the pin 114 to a supporting bracket 115. The supporting bracket 115 is attached to the underside of the base plate 20. Affixed to the flattened portion 113 of the member 112 is the pin 116 which is engaged by the slot 117 in one end of the lever member 118. The lever member 118 is pivotally mounted on the mounting bracket 115 by means of pin 119.

The other end of the lever member 118 has an extended portion 120 which contains the bore 121 through which is passed rod member 122. The rod member 122 is held in engagement with the lever member extension 120 by means of the rod collar 123 and the spring 124. The tension of the spring 124 may be adjusted by setting the locking pair of lock nuts 126 in any desired position on the threaded end of the rod 122.

Mounted on the other end of the rod 122 is the tongue 128. The tongue 128 is coupled to the clevis 130 by a pin 132. The clevis 130 is mounted on the rod member 134 which is rigidly affixed to the sliding gib 98.

Also mounted on the underside of the mounting plate 20 is the bracket member 136. Affixed to the bracket member 136 is the block 137. The stop screw 138 passes through a threaded bore in the block 137 and is locked in position by the lock nut 139. Also mounted on the bracket 136 is the limit switch 140. Both the stop screw 138 and the limit switch 140 are adapted to be engaged by the lever member 118 upon operation of the mechanism, as will be hereinafter described.

When it is desired to assemble a cathode assembly by welding a cap to a tube and disc assembly, the operator will place a cathode cap 150 over the proper end of a tube 152 of a cathode tube and disc assembly and place this assembly over the end of the rod member 76, as shown in Figure 2. The tube and disc and cap assembly are more clearly shown in Figure 6 which is drawn to show the relative positions of the various parts involved in gauging and welding the cap to the tube at the time the welds are made.

After having placed the unwelded electrode assembly into position over the end of the rod member 76, the operator will actuate the member 112, extending below the base plate 20, moving it to the position 112', as shown in construction lines in Figure 3. This motion of the member 112 results in moving lever member 118 into the position also shown in construction lines and num-

bered 118' whereat motion is arrested by the stop screw 138 and its end portion 120' actuates the limit switch 140. When the lever member 118' is in this depressed position, the lever end portion 120' will bear against the spring 124' which in turn bears against the lock nuts 126' drawing the rod 122 to the right, as viewed in Figure 3, to the position 122' causing the rod member 134 to assume the position 134' and causing the end 111 of the micrometer stem and gauge faces 104 to move to the right and engage the tube disc and cap assembly, as shown in Figure 6, with a force as determined by the degree of compression of spring 124'.

With the parts in this position, the end 111 of the micrometer shaft will bear against the cathode assembly cap 150, holding it firmly against the end face of the rod 76. The end faces 104 of the gauge plate extensions bear against the face 20 of the disc 154 causing it to depress the spring loaded members 88 back into the plug 80, with the result that the action of the springs 90 holds the disc 154 firmly against the gauge plate faces 104. Thus the relation between the left hand 25 face of the disc 154, as viewed in Figure 6, and the left hand or outer surface of the cap 150 is firmly established by the gauging means as to both parallel plane alignment and longitudinal dimensional relation.

There is provided a suitable electric current timing means 151 which may be any one of a number of conventional timers and which receives power from the power lines 153 and 155 and is initiated by the closure of microswitch 140 to pass current through leads 8 and 19 to the solenoid control coil 9 of the one-revolution clutch 6. The timer 151 is adjusted to energize the coil 9 for a sufficient period to permit the one-revolution clutch to commence its operation and to de-40 energize the coil for a sufficient time before the completion of one revolution of the clutch in order to prevent a second operation of the clutch from occurring.

When the operator has actuated the member 112 and the lever 118 to engage the cathode assembly parts within the welding and gauging means, as hereinbefore described and as shown in Figure 6, further motion of the members 112 and 118 will not move the gauge and micrometer assembly but will merely compress the spring 124 as shown at 124' as the lever 118 moves to its extreme position where it actuates the limit switch 140 and its motion is arrested by the end of the stop screw 138.

Closing the contact of the limit switch 140 initiates the timing means 151 actuating the one-revolution clutch. Upon operation of the one-revolution clutch, the member 30 carrying the cam members 33 will be rotated for half a revolution, as previously described. As the rotating cam members 33 engage the outer ends of an oppositely disposed pair of welding electrode mounting blocks 38 the mounting blocks are cammed inwardly by the bevelled portion 160 of the leading edges of the cams 33 as the cams rotate in a clockwise direction, as viewed in Figure 5. The continued rotation of the member 30 and the cams 33 will cause the inner cam faces 162 to pass over the ends of the electrode mounting block 38 holding the electrode mounting block in radially inward position during the period of dwell of the cam faces 162; and further rotation will allow the mounting block 38 to move outwardly over the bevelled trailing edges 161 of the cam in response to the urging by the spring member 23.

When a cam moves a mounting block inwardly the yoke member 42 which is carried by the mounting block will bear against the upper portion of the spring 52. The other end of the spring, bearing against the member 50, will carry the electrode sleeve and the electrode holder inwardly into contact with the cathode cap, as shown in Figure 6. After travel of the electrode and electrode sleeve has been arrested by contact of the electrode tip with the cathode cap, further motion of the block 38 and the yoke member 42 will serve only to compress the spring 52. This spring compression provides an electrode tip force and an electrode having yieldable contact with the cathode cap.

Referring to Figure 5, when the rotatable member 31 is rotated clockwise to a position where the cam members 33 have depressed the vertically lying electrode mounting blocks 38, the button 35, shown at the bottom of the member 31 in Figure 5, will have rotated to a position where it will actuate the microswitch 144. Upon actuating limit switch 144, welding timer 70 will be operated and welding current passed through welding cable 66, jumper lead 64 to the block 60 and thence through the electrode sleeve 48, electrode holder 54 and electrode tip 56 through the cathode cap 150, the cathode tube 152, the rod 76, which is made of a conductive material such as brass, through the opposite side of the cathode sleeve 152 and the opposite side of the cathode cap 150 into the electrode tip 56, electrode holder 54, sleeve 48, block 62, jumper 68 and the welding cable 69 back to the welding timer. At the points of contact of the two electrodes 56 to the cathode cap 150, resistance welds will be formed between the cap 150 and the tube 152 in a conventional manner. The period of dwell or the length of the inner face 152 of the cam 33 may be selected to provide a sufficiently long time duration of contact for the electrodes upon the cathode cap to provide a suitable welding condition. With the apparatus as described and the member 30 making a half a revolution with each operation, it will be obvious that the two pairs of welding electrodes are each depressed once with each operation of the one-revolution clutch. Thus, two pairs, or a total of four welds, will be made on the cathode assembly with each operation of the welding apparatus.

After the one-revolution clutch has completed its cycle and the welding timer has interrupted the flow of welding current, the operator may return the member 112 to its normal position whereupon, by the action of rod 122, the gib 98 carries the micrometer and gauge assembly back away from the cathode assembly to a position as shown in Figure 2. The operator may then remove the welded assembly from the machine and place into the machine a new assembly for welding.

In my copending application, Serial No. 75,577, filed February 10, 1949, there is disclosed a method and apparatus for mounting the disc 154 on the tube 152 by forming beads in the tube on each side of the disc.

In the copending application of Thomas H. Briggs, Jr., Serial No. 75,845, filed February 11, 1949, now U. S. Patent 2,551,871, granted May 8, 1951, there is disclosed a method and apparatus for striking the beads, closing the beads and causing them to bear flatly against the disc, as shown in the present application.

It is extremely difficult to maintain the extreme degree of accuracy of dimension required

between the face of the cap member 150 and the face of the disc 154 by relying on providing the proper length of tubing 152 extending beyond the face of the disc. This problem is further complicated by the inconsistencies occurring in the bend radius attained in the manufacture of a drawn cap such as member 150. The present invention provides a means for assembling the cap to the tube with the high degree of accuracy required since neither the length of the tube nor the dimensions of the cap determine the final central spacing of the face of the insulating disc from the face of the cap.

A particularly desirable feature of the present invention is that, when the cap and tube and disc assembly have been positioned in the gauging means and are accurately held in proper alignment, the welding operation is completed before the cap and tube and disc assembly are released by the gauging means. Thus, once the parts have been properly positioned, all of the welding is completed before the parts are released. Thus, there is assured accurate alignment between the parts.

25 What is claimed is:

1. A welding apparatus adapted to be associated with a welding current timer and comprising at least one pair of radially disposed opposed welding electrodes, individual means retaining each of said electrodes, means radially slidably mounting each of said electrode retaining means, means rotatable about the circumference of said mounting means for intermittently depressing said retaining means inwardly within said mounting means, said electrodes moving inwardly in response to the action of said depressing means on said retaining means and engaging opposite sides of parts to be welded together, and means for initiating a welding current timer to pass welding current through said electrodes and the parts when said electrodes are in engagement therewith.

2. A welding apparatus adapted to be associated with a welding current timer and comprising at least one pair of radially disposed opposed welding electrodes, individual means yieldably retaining each of said electrodes, means radially slidably mounting each of said electrode retaining means, means rotatable about the circumference of said mounting means for intermittently depressing said retaining means inwardly within said mounting means, intermittently rotating means actuating said rotatable depressing means, said electrodes moving inwardly in response to the action of said depressing means on said retaining means and yieldably engaging opposite sides of parts to be welded together, and means for initiating a welding current timer to pass welding current through said electrodes and the parts when said electrodes are in engagement therewith.

3. A welding apparatus adapted to be associated with a welding current timer and comprising at least one pair of radially disposed opposed welding electrodes, individual means yieldably retaining each of said electrodes, means radially slidably mounting each of said electrode retaining means, means rotatable about the circumference of said mounting means for intermittently depressing said retaining means inwardly within said mounting means, intermittently rotating means actuating said rotatable depressing means, said electrodes moving inwardly in response to the action of said depressing means on said retaining means and

yieldably engaging opposite sides of parts to be welded together, and means responsive to the position of said intermittently rotating means for initiating a welding current timer to pass welding current through said electrodes and the parts when said electrodes are in engagement therewith.

4. A welding apparatus adapted to be associated with a welding current timer and comprising a plurality of pairs of radially disposed opposed welding electrodes, individual means retaining each of said electrodes, means radially slidably mounting each of said electrode mounting means, means rotatable about the circumference of said mounting means for intermittently depressing successive opposed pairs of said retaining means inwardly within said mounting means, successive pairs of said electrodes moving inwardly in response to the action of said depressing means on said retaining means and engaging opposite sides of parts to be welded together, and means for successively initiating a welding current timer to pass welding current through each pair of electrodes and the parts to be welded when said electrodes are in engagement therewith.

5. A welding apparatus adapted to be associated with a welding current timer and comprising a plurality of pairs of radially disposed opposed welding electrodes, individual means retaining each of said electrodes, means radially slidably mounting each of said electrode mounting means, means rotatable about the circumference of said mounting means for intermittently depressing successive opposed pairs of said retaining means inwardly within said mounting means, intermittently rotating means actuating said rotatable depressing means, successive pairs of said electrodes moving inwardly in response to the action of said depressing means on said retaining means and engaging opposite sides of parts to be welded together, and means for successively initiating a welding current timer to pass welding current through each pair of electrodes and the parts to be welded when said electrodes are in engagement therewith.

6. A welding apparatus adapted to be associated with a welding current timer and comprising a plurality of pairs of radially disposed opposed welding electrodes, individual means retaining each of said electrodes, means radially slidably mounting each of said electrode mounting means, means rotatable about the circumference of said mounting means for intermittently depressing successive opposed pairs of said retaining means inwardly within said mounting means, intermittently rotating means actuating said rotatable depressing means, successive pairs of said electrodes moving inwardly in response to the action of said depressing means on said retaining means and engaging opposite sides of parts to be welded together, and means responsive to the position of said intermittently rotating means for successively initiating a welding current timer to pass welding current through each pair of electrodes and the parts to be welded when said electrodes are in engagement therewith.

7. A welding apparatus adapted to be associated with a welding current timer and comprising at least one pair of radially disposed opposed welding electrodes, individual means yieldably retaining each of said electrodes, means

radially slidably mounting each of said electrode retaining means, means rotatable about the circumference of said mounting means including cams for intermittently depressing said retaining means inwardly within said mounting means, intermittently rotating means actuating said rotatable depressing means, said electrodes moving inwardly in response to the action of said depressing means on said retaining means and yieldably engaging opposite sides of parts to be welded together, and means for initiating a welding current timer to pass welding current through said electrodes and the parts when said electrodes are in engagement therewith.

15 8. A welding apparatus adapted to be associated with a welding current timer and comprising at least one pair of radially disposed opposed welding electrodes, individual means yieldably retaining each of said electrodes, fixed means radially slidably mounting each of said electrode retaining means, means slidably mounting each of said electrode retaining means, means rotatable about the circumference of said mounting means for intermittently depressing said retaining means inwardly within said mounting means, intermittently rotating means including a one-revolution clutch actuating said depressing means, means controllable by an operator to initiate the operation of the one-revolution clutch, said electrodes moving inwardly in response to the action of said depressing means on said retaining means and yieldably engaging opposite sides of parts to be welded together, and means responsive to the position of said depressing means for initiating a welding current timer to pass welding current through said electrodes and the parts when said electrodes are in engagement therewith.
